UNITED STATES PATENT OFFICE.

HENRY W. MERRITT, OF SYRACUSE, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

970,076.

Specification of Letters Patent. Patented Sept. 13, 1910.

Application filed September 7, 1905. Serial No. 277,381.

To all whom it may concern:

Be it known that I, HENRY W. MERRITT, citizen of the United States, and resident of Syracuse, in the county of Onondaga and State of New York, have invented certain new and useful Improvements in Type-Writing Machines, of which the following is a specification.

My invention relates to typewriting machines and more especially to the type actions of such machines.

The principal object of my invention is to provide an improved type action for a front-strike typewriting machine.

My invention consists in certain features of construction and combinations and arrangements of parts, all of which will be fully set forth herein and particularly pointed out in the claims.

My invention is illustrated in the accompanying drawings in which.

Figure 1 is a front to rear vertical sectional view of a typewriting machine with some of the parts omitted. Fig. 2 is a view similar to Fig. 1 but with some of the parts shown in said figure omitted and showing a type bar and its connected parts in printing position. Fig. 3 is a rear view in transverse vertical section on the line x—x of Fig. 1.

The main frame of the machine shown in the drawings comprises a base portion 1 from which rise posts 2 that support a top plate 3. A platen 4 diagrammatically shown, is mounted on a carriage (not shown) which is mounted on the top plate 3 for transverse motion in any usual or suitable manner. Said carriage may be drawn toward the left by the usual spring drum 5, and may be provided with a feed rack 6, the motion of which is controlled by feed dogs 7 mounted on a dog rocker 8 that is pivotally mounted on a bracket 9 depending from the top plate 3; or the motion of said carriage may be controlled by any other suitable step-by-step feed device.

The type bars are mounted on a type bar segment 9 below the top plate 3. Said segment may be supported in any suitable manner, but as here shown it is made shiftable up and down, being guided by brackets 10 depending from the top plate 3. Said brackets are formed on their inner faces with ball races in which play anti-friction

balls or rollers 11 which also coöperate with corresponding race ways formed in the right and left-hand ends of the segment 9. Said segment may be shifted up and down by any suitable case shift device. So far as my invention is concerned the platen 4 may be made shiftable up and down instead of the segment 9. Front-strike upwardly and rearwardly swinging type bars 12 are pivotally mounted on the segment 9 in any suitable manner. As shown in the present instance said type bars are pivoted on a pivot wire 13 that lies in a slot formed in the upper face of the segment 9, and each of said type bars is mounted in one of a series of radial slots 14 formed in the segment 9. Each of the type bars 12 carries two types 15, one or another of which is adapted to strike against the front face of the platen 4 according as the segment 9 is in its upper or lower position. The free ends of the type bars 12 normally rest on a segmental pad 16 which is supported by rods 17 projecting toward the front of the machine from the segment 9. Character keys 18 are mounted on the forward ends of key levers 19, which at their rear ends are pivoted on a transverse pivot rod 20 which is mounted at its ends in the side plates of the base portion 1 of the main frame. Each of said key levers is formed near its rear end with a notch that hooks under the pivot rod 20. Said key levers are spaced apart and guided at their rear ends by a comb plate 21 mounted in the main frame just back of the pivot rod 20 and having formed therein a series of vertical slots, one, for each of said key levers. The comb plate 21 is secured at its ends to the side plates of the base portion 1 of the main frame by screws 22 passing through ears 23 of said comb plate and threaded into said side plates. The key levers 19 are guided near their forward ends by a comb plate 24 secured to a cross-bar 25 of the main frame, which cross-bar lies above the series of key levers and has secured to its under side an arresting pad 26. Angular sub-levers 27 are pivoted on a rod 28 that lies beneath the series of key levers 19 and is mounted on its ends in the side plates of the base portion 1 of the main frame. Each of said sub-levers has an up-standing arm, to the upper end of which at 29 there is pivoted the end of a link

30, the forward end of which is pivoted at 31 to one of the type bars 12. Each of the sub-levers 27 has a rearwardly projecting arm 32, the upper surface of which is engaged by a member forming part of or mounted on one of the key levers 19. Said member preferably consists of a roller 33 journaled on a headed pin or screw 34 projecting from one side of the key lever 19. 5 The rollers 33 are preferably grooved on their peripheries, the upper edge of the arm 32 of each of the sub-levers lying in the groove in the periphery of one of the rollers 33. Each of the sub-levers 27 is formed 10 with a forwardly projecting arm 35 to which is connected the upper end of a returning spring 36, the lower end of which is connected to a cross-bar 37 which is secured at its ends to the side plates 1 by screws 38 15 passing through ears 39 of said bar 37 and threaded into said side plates. The construction is such that when any key 18 is operated the corresponding key lever 19 is depressed and the roller 33 on said key 20 lever depresses the rearwardly extending arm 32 of the corresponding sub-lever, thus moving the upstanding arm of said sub-lever toward the back of the machine and causing the link 30 to swing the corresponding type 25 bar 12 to the printing point, all as indicated in Fig. 2. As the arm 32 and the key lever 19 move about different centers, the roller 33 will roll a short distance along the arm 32 of the sub-lever when the key is depressed. The 30 type bar, the sub-lever and the key lever are all restored to normal position by the spring 36. The sub-levers 27 are spaced apart on the pivot rod 28 by collars 27'. By reference to Fig. 3 it will be perceived that the system 35 of key levers is much wider than the system of type bars and operating links 30, so that those sub-levers 27 that are near the right-hand and left-hand sides of the system have their upright arms bent in toward 40 the middle of the machine in order to bring the upper ends of said arms into proper relation to the type bars. It results from this construction that when one of the type bars near the end of the segment is operated 45 by its key lever and sub-lever, the resistance of the link 30 on the upper end of the sub-lever tends, during the key depression, to turn or twist the sub-lever about its pivotal point in such manner as to throw the rearwardly extending arm 32 thereof laterally toward the center of the machine. This 50 twisting tendency is resisted by the side of the groove in the roller 33, as well as by the collars 27', so that the sub-lever is not allowed to bind between the two adjacent collars 27', and affords a fore and aft movement of the sub-lever without effecting a binding thereof on its pivotal bearings.

A universal bar 40 extends across the machine beneath the arms 32 of the sub-levers.

Said universal bar is connected at its ends to arms 41 which in turn are pivotally mounted on the pivot rod 28. It will be perceived that when any character key is operated the universal bar 40 is depressed by the corresponding sub-lever. Said universal bar has a rearwardly extending centrally located arm 42 having a shouldered and headed screw 43 threaded into it near its rear end. Said screw passes loosely through an elongated slot 44 formed in the lower end of a link 45, the upper end of which is pivoted to the forward end of an arm 46 that extends toward the front of the machine from the dog rocker 7. The screw 43 does not normally stand in the bottom of the slot 44, but stands a short distance above the bottom of said slot so that the link 45 and the dog rocker 7 do not begin to move until the key lever, sub-lever, and type bar have already made a part of their stroke and have acquired some momentum. In order that the amount of lost motion between the screw 43 and the bottom of the slot 44 may be regulated, the lower end of the link 45 is made in a separate piece from the upper end of said link and is threaded on to the upper end of said link so that the length of the link may be adjusted by screwing said lower end up or down. The dog rocker and universal bar are restored to normal position by a spring 47, compressed between the bracket 8 and the upstanding arm of said dog rocker on which the dogs 6 are mounted.

In most front-strike type actions there are a number of loose joints between the key and the type bar and it is desirable to have as few as possible of these loose joints between the type bar and the universal bar. It is 105 desirable to have the escapement, which is controlled by the universal bar, let off as soon as possible after the type rebounds from the platen and every loose joint between the type bar and the universal bar 110 lessens the precision with which the let-off can be controlled. In a type action of the general character set forth in this case the universal bar controls the escapement more exactly if said universal bar is operated by 115 the sub-levers than it does if operated by the key levers. It is not new to operate the universal bar by means of the sub-levers of a front-strike typewriter, but it is new to mount the universal bar beneath the horizontal arms of said sub-levers, and this is the simplest scheme for this purpose with which I am acquainted. The universal bar is thus simply a straight bar lying beneath horizontal parts having an up and down 120 motion; and this is a simpler construction than those in which the universal bar moves horizontally and is operated by the upstanding arms of the sub-levers.

Various changes in the details of construc-

tion and arrangement may be made without departing from my invention.

What I claim as new and desire to secure by Letters Patent, is:—

- 5 1. In a typewriting machine, the combination of a key lever; a type bar; a sub-lever between said key lever and type bar, said sub-lever being pivoted below said key lever and having an upstanding arm connected 10 with said type bar and having below the key lever a rearwardly extending arm and a forwardly extending arm; a member on said key lever engaging one of the last mentioned arms; and a returning spring connected to 15 the other of said arms.
2. In a typewriting machine, the combination of a key lever; a sub-lever having three arms; a type bar connected with one of said arms; a grooved roller mounted on 20 said key lever and engaging another of said arms; and a returning spring connected with the other of said arms.
3. In a typewriting machine, the combination of a series of key levers; a series of 25 angular sub-levers, each having an upstanding arm and an approximately horizontal arm; a series of type bars, each connected with one of said upstanding arms, said series of type bars being of less width than 30 said series of key levers and the upstanding arms of those sub-levers near the ends of the series being bent toward the middle of the machine to bring them into proper relation with their respective type bars; and grooved 35 rollers connecting said key levers and said approximately horizontal arms of said sub-levers.
4. In a typewriting machine, the combination of a series of key levers; a series of 40 type bars of less width than said series of key levers; a series of sub-levers, one for each of said key levers, each of said sub-levers having an upstanding arm connected with one of said type bars and having also an approximately 45 horizontal arm; and a grooved roller connecting each of said key levers and said approximately horizontal arm of the corresponding sub-lever.
5. In a front-strike typewriting machine, 50 the combination of a series of key levers; a series of upwardly and rearwardly striking type bars; a series of sub-levers, each having an upstanding arm connected with one of said type bars and an approximately horizontal arm, the upstanding arms vibrating fore and aft of the machine; and a universal bar operated by said approximately horizontal arms.
6. In a front-strike typewriting machine, 55 the combination of a series of key levers; a series of type bars; a series of sub-levers each connecting one of said key levers with one of said type bars; a rod on which said 60 sub-levers are pivotally mounted; and a 65

universal bar pivotally mounted on said rod and adapted to be operated by any of said sub-levers.

7. In a front-strike typewriting machine, the combination of a series of key levers; a series of type bars; a series of sub-levers each having an upstanding arm connected with one of said type bars and an approximately horizontal arm; a rod on which said sub-levers are pivotally mounted; means whereby each of said key levers operates one of said approximately horizontal arms; and a universal bar pivotally mounted on said rod and adapted to be operated by any of said approximately horizontal arms. 75

8. In a typewriting machine, the combination of a series of key levers pivoted at their rear ends; a series of upstanding sub-levers, each having an approximately horizontal arm extending below said key levers; a universal bar lying below said approximately horizontal arms and adapted to be depressed by any one of them; and upwardly and rearwardly striking type bars operated by said sub-levers. 85

9. In a front strike typewriting machine, the combination of a series of key levers, a series of angular sub-levers each having an upstanding arm and an approximately horizontal arm, a series of type bars each connected with one of said upstanding arms, and grooved rollers mounted on said key levers and engaging said approximately horizontal arms on said sub-levers. 95

10. In a front strike typewriting machine, the combination of a series of upwardly and rearwardly striking type bars, a series of three-arm sub-levers each connected by one of its arms with a type bar, a series of restoring springs each connected to an arm of one of said sub-levers, and a series of key levers provided with anti-friction rollers each adapted to bear on one of the arms of the associated sub-lever. 105

11. In a front strike typewriting machine, the combination of a series of key levers, a series of upwardly and rearwardly striking type bars, a series of sub-levers operated by said key levers and each having an upstanding arm connected with one of said type bars and an approximately horizontal arm, the said upstanding arms vibrating fore and aft of the machine and a universal bar operated by said approximately horizontal arms. 115

12. In a front strike typewriting machine, the combination of a series of key levers; a series of sub-levers each having an upstanding arm, a series of type bars each connected with the upstanding arm of a sub-lever, said series of type bars being of less width than said series of key levers, and the upstanding arms of those sub-levers near the ends of the series being bent toward the middle of the machine to bring them into proper relation with their respective type bars; and 120

grooved rollers, each connecting one of said key levers with a sub-lever, each roller being mounted on one of the levers and the other lever running in the groove of the roller and said rollers operating to transmit motion from the key lever to the sub-lever and to take the side thrust due to the bent form of the upstanding arm of the sub-lever.

13. In a front strike typewriting machine, 10 the combination of a series of key levers, a series of type bars of less width than said series of key levers, a series of sub-levers one for each key lever, each of said sub-levers having an upstanding arm and an approximately horizontal arm, and a series of 15 grooved rollers, one connecting each of said key levers with the horizontal arm of the corresponding sub-lever, said roller being mounted on one of said levers and the other lever running in the groove of the roller and said roller operating to transmit motion from the key lever to the sub-lever and also to take the side thrust due to the difference 20 in width of the system of type bars and the 25 system of key levers.

14. In a front-strike typewriting machine, the combination of a series of key levers, a series of type bars of less width than said series of key levers, a series of sub-levers 30 each having an upstanding arm connected with a type bar and a horizontal arm, the upstanding arms of those sub-levers near the ends of the series being bent toward the middle of the machine to bring them into 35 proper relation with their respective type bars, and the horizontal arms being disposed below the key levers; and connections between the several key levers and the hori-

zontal arms of the sub-levers comprising 40 grooved rollers, each roller being mounted on one of the levers and the other lever running in a groove of the roller and said roller operating to transmit motion from the key lever to the sub-lever and to take the side thrust due to the bent form of the upstanding arm of the sub-lever. 45

15. In a front-strike typewriting machine, the combination of a series of key levers, a series of type bars of less width than said series of key levers, a fulcrum rod below 50 said series of key levers, a series of sub-levers pivoted on said fulcrum rod and each having an upstanding arm and a horizontal arm, the upstanding arms of those sub-levers near the ends of the series being bent toward 55 the middle of the machine to bring them into proper relation with their respective type bars and the horizontal arms of the sub-levers being disposed below the key levers, and grooved rollers each connecting one of 60 said key levers with the horizontal arm of the sub-lever, each roller being mounted on one of the levers and the other lever running in a groove of the roller and said rollers operating to transmit motion from the 65 key lever to the sub-lever and to take the side thrust due to the bent form of the upstanding arm of the sub-lever.

Signed at Syracuse, in the county of Onondaga, and State of New York, this 5th day of September A. D. 1905.

HENRY W. MERRITT.
